United States Patent Office

Des. 226,157
Patented Jan. 30, 1973

226,157

TABLE

Thomas Winrow, 530 S. Sleigh St.,
Naperville, Ill. 60540

Filed Dec. 7, 1970, Ser. No. 26,321

Term of patent 14 years

Int. Cl. D6—03

U.S. Cl. D6—177

The figure is a perspective view of a table illustrating my new design.

The back of the table and the side not shown are substantially identical to the front of the table and the side shown, respectively.

I claim:

The ornamental design for a table, substantially as shown and described.
